UNITED STATES PATENT OFFICE.

THOMAS U. WHITE, OF PITTSBURGH, AND JOHN E. GARDNER, OF WILKINSBURG, PENNSYLVANIA, ASSIGNORS TO WESTINGHOUSE ELECTRIC & MANUFACTURING COMPANY, A CORPORATION OF PENNSYLVANIA.

SIGNALING SYSTEM.

Application filed November 15, 1924. Serial No. 750,069.

Our invention relates, in general, to signaling systems and more particularly to systems for supervising and controlling, from a central point, remotely-disposed power apparatus.

One of the objects of our invention is to provide improved circuit arrangements for operating relays at a distant point or station in synchronism with relays at a central point or dispatcher's office.

Another object of our invention is to provide an improved driving or control circuit for operating relays at a dispatcher's office and station in a predetermined sequence.

Another object of our invention is to provide improved circuit arrangements whereby relays located at the dispatcher's office and relays located at the station may be operated alternately in a predetermined sequence.

Another object of our invention is to provide means whereby apparatus units in the distant station may be controlled and operated from a central point or dispatcher's office by means of predetermined codes of impulses after such unit has been selected.

A further object of our invention is to provide a group of selecting relays at the dispatcher's office and a group of selecting relays at the substation which are operated by a driving circuit that is closed a plurality of times to secure the selection of each apparatus unit.

A further object of our invention is to provide an improved circuit, exclusive of the driving circuit, for maintaining the relay selecting apparatus in both the dispatcher's office and station in normal condition.

A further object of our invention is to provide releasing means at the station that may be operated from the dispatcher's office by means of an impulse code.

A still further object of our invention is to provide means for automatically interrupting the action of the driving circuit whenever such releasing operation is brought about.

There are other objects of our invention which, together with those above described, will be explained in detail in the specification to follow.

In practicing our invention, we provide a group of counting relays at the dispatcher's office and a group of counting relays, corre-

sponding in number, at the station in which are located the apparatus units that it is desired to control. One group of auxiliary selecting relays is associated with each group of counting relays. A control or driving circuit is located at both the dispatcher's office and substation for operating the counting relays.

The counting relay groups and control circuits are connected together by means of a three-conductor trunk line, a ground return being used. It is, of course, obvious that a separate conductor common to the other three may be used to eliminate difficulties by reason of varying ground potential between the dispatcher's office and station.

At the dispatcher's office, a group of keys are provided, corresponding in number to the number of apparatus units that it is desired to operate. A starting key is also located at the office. In order that the dispatcher may be apprised of the condition of the apparatus units in the station, two signaling lamps are provided for each apparatus unit, one to indicate the operative condition of the unit and the other to indicate the inoperative condition of the unit.

In addition, at the dispatcher's office a signaling lamp is provided for each selecting relay so that the dispatcher is at all times apprised of the selecting position of the relay apparatus. Control and releasing devices and a starting key are also provided at the dispatcher's office.

When the dispatcher desires to operate an apparatus unit at the station or substation, he will operate the key associated with that particular unit in the proper direction and also the start key. As a result of this operation, the driving circuit functions to operate the relays in the counting relay groups in a predetermined sequence.

The driving circuit is so arranged that a counting relay at the dispatcher's office is first operated and, by a subsequent operation of the driving circuit, a counting relay at the station is operated. Then, by the action of the driving circuit, a counting relay at the dispatcher's office and a counting relay at the station are operated simultaneously. The operation of the latter counting relay brings about the operation of the selecting relay. This operation is repeated throughout the

operation of the relays in the counting chains. The relays in the auxiliary selecting groups at the dispatcher's office and station are thus operated simultaneously in a predetermined sequence.

When the proper apparatus unit is selected, the action of the driving circuit is interrupted and the dispatcher will then operate the control device for either closing or tripping the circuit interrupter at the station. By the operation of these devices, a predetermined number of impulses are sent over the control circuit whereby the circuit interrupter is operated. The circuit interrupter, upon operating, sends back an impulse of current to the dispatcher's office to actuate the signaling devices associated with this interrupter in order to apprise the dispatcher of the operation. This return indication also brings about the initiation of the operation of the driving circuit.

It will be obvious that the peculiar action of the driving circuit by which a relay in the counting chain at the station is first operated, and then a relay in the counting chain at the dispatcher's office, followed by the simultaneous energization of a counting relay at both the dispatcher's office and station to bring about the operation of a selecting relay at each point, provides positive operation of the selecting apparatus. This is true by reason of the fact that it is necessary to have a check-back impulse indicative of the operation of the counting relay at the station before the counting relay at the dispatcher's office is operated.

A similar circuit arrangement is provided to insure the proper action of the driving circuit when the selecting relays are operated. That is, unless the selecting relays are operated, the driving circuit is prevented from being closed. These precautionary circuits are provided to insure proper operation, even though the trunk line connecting the substation and dispatcher's office over which the relay apparatus is operated should lie adjacent to power lines, thereby being subject to induced currents therefrom.

As before described, after the operation of the apparatus unit, the driving circuit again functions to bring about the subsequent operation of the remaining selecting relays at both the station and dispatcher's office in a predetermined sequence. After all these relays are operated, the apparatus restores to normal.

In the event that an apparatus unit at the station operates under the control of automatic devices responsive to circuit conditions or is operated manually by an operator, or such action occurs by reason of defective mechanical structure, the selecting apparatus is operated in substantially the same manner as before and the supervisory signaling devices associated with the apparatus unit

that has been actuated are controlled to give an indication showing the operation of the unit.

Referirng now more particularly to Fig. 1, relays 100 to 123, inclusive, comprise the group of counting relays at the dispatcher's office. Relay 124 is a slow-releasing relay, while relays 125 to 127, inclusive, are relays that are controlled by certain operations of the counting relays. A key K is of the usual single-throw, non-locking type.

In Fig. 2, a key K-3 is a type of special double-throw key. There is one such key for each apparatus unit that it is desired to control. Keys, such as K-3, are so constructed that, when operated, they lock in a certain position. Thus, in order to force the springs 218 and 221 into engagement with their working contacts and the springs 219 and 222 from engagement with their resting contacts, it is necessary to turn the operating member 220. When the key is turned in the opposite direction, the springs are restored to the position shown. The key is a special form of twist key.

Release device 290, closing device 200 and tripping device 201 are special types of calling devices similar to those used in the automatic telephone art. A calling device that will operate satisfactorily is shown on pages 95 16 and 18 of the book entitled "Automatic Telephone Practice", third edition, by Harry E. Hershey. The construction of these devices is so modified that it is only possible to produce a definite number of interruptions 100 by any one of them.

In the present case, the device 200 is adapted to produce two interruptions in the control circuit, the device 201 four interruptions and the device 290 six interruptions. The device may be arranged to do this by taking 105 the ordinary calling device and placing a pin in the particular finger hole necessary, then covering the remaining finger holes with a cover so that, in order to operate the device, 110 the pin must be used.

Relays 202 to 206, inclusive, are associated with each key, such as K-3. The relays 202 and 203 have their armatures mechanically interlocked so that, when the relay 202 operates and is deenergized, the armatures 223 and 224 are maintained in their operative position by the latching action of the armature 225 of the relay 203. The relays 204 and 205 have their armatures so arranged that, 120 when the relay 204 is energized and deenergized, the armatures 228, 229 and 230 are maintained in their attracted position by the action of the armature 231 of the relay 205. The operation of the relay 204 controls the 125 operation of the signaling devices 226 and 227. The relay 206 is an ordinary type of slow-releasing relay. Relays 207 to 216, inclusive, comprise the group of selecting relays at the dispatcher's office. Keys K-1, 130

K-2 and K-16 are associated with the control devices 200, 201 and 290, respectively. These keys are of the usual single-throw locking type.

5 In Fig. 3, relays 300 to 317, inclusive, comprise the driving circuit at the dispatcher's office. Key K-14 is an ordinary type of non-locking, single-throw key.

In Fig. 4, relays, such as 400 to 402, inclusive, are associated with each circuit interrupter, such as C. The relays, such as 400, associated with each circuit interrupter are slow to pick up and slow to release. That is, they are so constructed that, when their circuit is closed, they require an appreciable time to energize and, when their circuit is opened, an appreciable time is required to deenergize. The relays 405 to 414, inclusive, comprise the relays of the selecting group at the substation.

20 Relays 500 to 519, inclusive, (Fig. 5) comprise the driving circuit at the substation.

Relays 600 to 623, inclusive, of Fig. 6 comprise the counting chain at the dispatcher's office. Relay 690 and relays 624 to 626, inclusive, are of the usual type and control certain operations of the counting relays.

25 In Fig. 7, relays 700 to 721, inclusive, control the operation of the circuit interrupters as well as the reoperation of the driving circuit under certain conditions as will appear.

Having briefly described and apparatus shown in the drawings, we will now explain its detailed operation. For this purpose, it 30 will be assumed that the circuit interrupter C at the station is in a tripped position and the dispatcher desires to close it. To accomplish this result, the dispatcher will operate the key K-3 so that the springs assume a position opposite to that shown. By this operation, ground is removed from the conductor 27 that extends to the key K-13 for a reason that will appear subsequently. In order to 35 initiate the operation of the driving circuit, the dispatcher will operate the key K-14 momentarily.

Normally, there is a circuit completed that 40 extends from ground by way of holding relay 301, back contact and armature 325, back contact and armature 332, trunk conductor 370, armature 520 and its back contact, holding relay 506, and armature 534 and its back contact to battery. The relay 301 is energized to open the locking circuit of the relay 300 at 45 armature 321, and to open one point in the circuit of the relay 306 at armature 322.

At the substation, the relay 506 is operated to 50 prepare a starting circuit at armature 531, to open the circuit of the relay 503 at armature 532, and to prepare a circuit for the relay 709 at armature 530.

Now, when the key K-14 at the dispatcher's office is depressed, a circuit is completed 55 that extends from ground by way of working contact and said spring, armature 324 and its

back contact and relay 302 to battery. The relay 302 is energized to prepare a circuit for the relay 303 over a path that extends from ground by way of back contact and armature 319, armature 323 and its front contact, relay 303 and relay 302 to battery.

When the key K-14 is released, the short-circuit is removed from the relay 303 and it is energized. The relay 303, upon operating, 60 opens another point in the original energizing circuit for the relay 302 at armature 324, and at armature 325 opens the previously traced holding circuit, including the holding relays 301 and 506. The relay 301 is de-65 energized to prepare a locking circuit for the relay 300 at armature 321 and to complete a circuit, at armature 322, that extends from ground by way of back contact and armature 320 and relay 306 to battery. The relay 306 is energized to prepare one point in the 70 driving circuit at armature 329.

At the substation, the relay 506 is deenergized to prepare a locking circuit for the relay 509 at armature 530, to prepare a circuit for the starting relay 708 at armature 531, 75 and to complete a circuit at armature 532 that extends from ground by way of armature 539 and its back contact, back contact and armature 532, and relay 503 to battery. The relay 503 is energized to close the driving circuit 80 at armature 525.

The driving circuit now extends over a path from battery B by way of back contact and armature 430, line relay 313, back contact and armature 350, armature 329 and its 85 front contact, armature 331 and its back contact, trunk conductor 372, back contact and armature 523, armature 524 and its back contact, front contact and armature 525, armature 541 and its back contact, line relay 514, 90 and armature 553 and its back contact to ground. The line relays 313 and 514 are energized over the above circuit.

The line relay 313 is operated to complete a circuit for the relay 311 at armature 341. 95 The relay 311 is operated to open one point in the locking circuit of the relays 314 and 315 at armature 336, and to complete a circuit at armature 337 that extends from ground by way of armature 184 and its back contact, 100 conductor 24, armature 342 and its back contact, armature 337 and its front contact, relay 312 and relay 311 to battery. The relay 312 is not energized so long as the original energizing circuit for the relay 311 is maintained.

At the substation, the line relay 514, upon 105 operating, completes a circuit for the relay 516 at armature 551, and at armature 550 closes a circuit for the relay 505. The relay 516 is operated to open one point in the locking circuit of the relays 512 and 513, and to 110 complete a circuit at armature 557 over a path that extends from ground by way of armature 687 and its back contact, conductor 469, armature 548 and its back contact, armature 115 120 125 130

ture 557 and its front contact, relay 515 and relay 516 to battery. The relay 515 is not operated by reason of the fact that it is short-circuited so long as the original energizing circuit of the relay 516 is closed.

10 The relay 505 is operated to establish a locking circuit for itself at armature 529 and to complete a circuit that extends from ground by way of front contact and armature 528, conductor 454, armature 682 and its back contact, armature 631 and its back contact, counting relay 600, armature 684 and its back contact, back contact and armature 680, and armature 683 and its back contact to battery.

15 The counting relay 600 is energized over the above-traced circuit and it operates to complete a circuit at armature 627 that extends from ground by way of armature 686 and its back contact, armature 627 and its front contact, relay 601, relay 600, armature 684 and its back contact, back contact and armature 680, and armature 683 and its back contact to battery. This circuit is not effective so long as the original energizing circuit for the relay 600 is maintained.

20 Another result of the operation of the relay 600 is that, at armature 628, a circuit is completed that extends from ground by way of armature 544 and its back contact, conductor 453, armature 628 and its front contact, armature 633 and its back contact, conductor 452, relay 502 and back contact and armature 526 to battery. The relay 502 is operated to open the circuits of the line relays 514 and 313 at armature 524.

25 The relay 313 is deenergized to remove the short-circuit from the relay 312. The relay 312 is operated to open another point in the circuit of the relay 313, at armature 340, to open another point in the circuit of the relay 311 at armature 339, and to complete a circuit at armature 338 over a path that extends from ground upon grounded conductor 24 by way of armature 338 and its front contact, and relay 317 to battery. The relay 317 is operated to prepare a circuit for the line relay 316 at armature 350, and to establish a locking circuit for itself at armature 351.

30 The line relay 514 at the substation, upon being deenergized, opens the original energizing circuit for the relay 505 at armature 550, and at armature 551 removes the short-circuit from the relay 515. The relay 515 is operated to open another point in the original energizing circuit of the relay 516 at armature 552, to open another point in the circuit of the line relay 514 at armature 553, to remove battery from conductor 458 at armature 554 and to complete a circuit at armature 555 for the relay 510.

35 The relay 510 is operated to establish a locking circuit for itself at armature 542, to complete a circuit for the relay 504 at armature 540 and to prepare the driving circuit at armature 541. The relay 504 is en-

ergized to open the circuit of the relay 502 at armature 526, and to establish a locking circuit for itself at armature 527. The opening of the circuit of the relay 502 causes this relay to deenergize to complete the driving 70 circuit.

The driving circuit now extends over a path from ground by way of back contact and armature 346, line relay 316, front contact and armature 350, armature 329 and its front contact, armature 331 and its back contact, trunk conductor 372, back contact and armature 523, armature 524 and its back contact, front contact and armature 525, armature 541 and its front contact, line relay 80 511, and armature 547 and its back contact to battery. The line relays 316 and 511 are energized over the above circuit.

Upon operating, the relay 316, at armature 349, completes a circuit for the relay 314, and at armature 348 places ground upon conductor 23. The relay 314 operates to open the circuit of the relays 311 and 312 at armature 342, and at armature 343 prepares a circuit for the relay 315. The relay 312 is deenergized to connect ground to conductor 22 at armature 338, to prepare a circuit for the relay 311 at armature 339, and to prepare a circuit for the line relay 313 at armature 340. The relay 311 is deenergized to open 95 one point in the circuit of the relay 312, and to complete a circuit that extends from ground upon grounded conductor 24 by way of back contact and armature 336, armature 343 and its front contact, relay 315 and relay 100 314 to battery. This circuit is not effective to energize the relay 315 so long as the original energizing circuit for the relay 314 is maintained.

The grounding of conductor 23 completes 105 a circuit that extends from ground by way of armature 188 and its back contact, armature 151 and its back contact, relay 111, armature 185 and its back contact, back contact and armature 158, and back contact and armature 187 to battery. The counting relay 111 is energized over the above circuit and operates to complete a circuit at armature 154 that extends from ground by way of armature 183 and its back contact, armature 154 and its front contact, relay 110, relay 111, armature 185 and its back contact, back contact and armature 158, and back contact and armature 187 to battery. The relay 110 is not energized until the original energizing 120 circuit for the relay 111 is opened.

Another result of the operation of the relay 111 is that, at armature 155, a circuit is completed that extends from ground upon grounded conductor 24, by way of armature 338 and its back contact, conductor 22, armature 155 and its front contact, armature 153 and its back contact, conductor 21, back contact and armature 326, and relay 307 to battery. The relay 307 is energized to open the 130

circuit of the slow-releasing relay 305 at armature 330, to place battery upon conductor 29 at the front contact of this armature, to open the circuits of the line relays 316 and 511 at armature 331, and to prepare a locking circuit for itself at armature 395. The connection of battery to conductor 29 prepares a circuit for the selecting relay 216.

The line relay 316 is deenergized to open 10 the previously traced circuit for the counting relay 111 at armature 348, and to remove the short-circuit from the relay 315 at armature 349. The relay 315 is operated to open one point in the circuit of the relay 316 at armature 346, to open another point in the original energizing circuit of the relay 314 at armature 345, and to prepare a locking circuit 15 at armature 344 for the relay 304. Another result of the operation of the relay 315 is that the locking circuit of the relay 317 is opened 20 and this relay is deenergized to prepare a circuit for the line relay 313.

When the original circuit for the relay 111 is opened, the short-circuit is removed from 25 the relay 110 and this relay is permitted to operate. The relay 110, upon operating, opens another point in the original energizing circuit of the relay 111 at armature 151, prepares a circuit for the counting relay 123 at armature 150, and completes a circuit at armature 30 149 that extends from ground by way of armature 177 and its back contact, armature 149 and its front contact, and relay 127 to battery. The relay 127 is energized to connect the impulsive circuit to the counting relay 123 at armature 188.

Another result of the operation of the relay 110 is that, at armature 152, a circuit is completed that extends from ground by way 40 of armature 183 and its back contact, armature 152 and its front contact, conductor 10, and relay 308 to battery.

A still further result of the operation of the relay 110 is that the circuit of the relay 307 is opened at armature 153. The relay 307 is deenergized to remove battery from conductor 29, to again complete the circuit of the slow-releasing relay 305 at armature 330, and to close one point in the driving circuit at armature 331. The relay 308 is energized to connect the signaling conductors 370 and 371 to the conductors 31 and 30, respectively, that extend to multiple contacts of the several selecting relays 207 to 216, inclusive. In the 55 ordinary selecting operation, the slow-acting relay 305 is not deenergized while the relay 307 is energized.

At the substation, the line relay 511 is operated to complete a circuit for the relay 513. The relay 513 is energized to open the circuit 60 of the relays 515 and 516 at armature 548, and to prepare a circuit for the relay 512 at armature 549. The relay 515 is deenergized to prepare a circuit for the relay 516 at armature 552, to prepare a circuit for the relay 514

at armature 553, to place battery upon the conductor 458 at armature 554, and to open the original energizing circuit of the relay 510 at armature 555.

The relay 516 is deenergized to open one point in the circuit of the relay 515 at armature 557, and to complete a circuit, at armature 556, that extends from ground upon grounded conductor 469 by way of back contact and armature 556, armature 549 and its front contact, relay 512 and relay 513 to battery. This circuit is not effective to energize the relay 512 so long as the original energizing circuit for the relay 513 is maintained.

When the circuit of the line relay 511 is opened, as previously described, this relay is deenergized to remove the short-circuit from the relay 512. The relay 512, upon operating, removes ground from conductor 453 at armature 544, opens the locking circuit of the relay 505 at armature 545, opens another point in the original energizing circuit of the relay 513 at armature 546, and at armature 547 opens another point in the circuit of the line relay 511. By the removal of ground from conductor 453, another point in the circuit of the relay 502 is opened.

The relay 505 is deenergized to remove ground from conductor 454, whereby the original energizing circuit of the counting relay 600 is opened. The counting relay 601 is immediately operated by reason of the fact that the opening of the circuit of the relay 600 also removes the short-circuit from the relay 601. The relay 601, upon operating, opens another point in the original energizing circuit of the relay 600 at armature 631, prepares a circuit for the counting relay 612 at armature 630, and at armature 629 completes a circuit that extends from ground by way of armature 658 and its back contact, armature 629 and its front contact, and relay 690 to battery. The relay 690 is energized to prepare one point in the impulsing circuit that includes the counting relay 612 at armature 682.

Another result of the operation of the relay 601 is that, at armature 632, a circuit is completed that extends from ground by way of armature 686 and its back contact, armature 632 and its front contact, conductor 451, and relay 500 to battery.

A still further result of the operation of the relay 601 is that another point in the circuit of the relay 502 is opened at armature 633. The relay 500 is operated to connect the signaling conductors 370 and 371 to the conductors 463 and 450, respectively, at armatures 521 and 520.

The operation of the counting relay 601 also completes a circuit that extends from ground by way of back contact and armature 668, front contact and armature 640, conductor 456 and relay 519 to battery. The relay 519 is operated to complete a circuit for the relay 517 at armature 560. The relay 517

is energized to open the locking circuit of the relay 510 at armature 558. The relay 510 is deenergized to prepare a circuit for the line relay 514.

5 The driving circuit is now completed over a path that extends from battery by way of back contact and armature 340, line relay 313, back contact and armature 350, armature 329 and its front contact, armature 331 and its 10 back contact, conductor 372, back contact and armature 523, armature 524 and its back contact, front contact and armature 525, armature 541 and its back contact, line relay 514, and armature 553 and its back contact to 15 ground. The line relays 313 and 514 are energized over this circuit.

The relay 313 operates to complete a circuit for the relay 311. The relay 311 is energized to prepare a circuit for the relay 312 20 and to open the circuits of the relays 314 and 315. The relay 315 is deenergized to prepare a circuit for the relay 316 and to open one point in the locking circuit of the relay 304. The relay 314 is deenergized to 25 complete the circuit of the relay 312. This circuit is not effective until the circuit of the relay 311 is opened by the deenergization of the relay 313.

At the substation, the relay 514 is operated 30 to complete a circuit for the relay 516. The relay 516 is energized to open the circuit of the relays 512 and 513. The relay 512 is deenergized to prepare a circuit for the relay 511 at armature 547, and to place ground upon 35 conductor 453 at armature 544. The relay 513 is deenergized to complete a circuit for the relay 515. This relay is not energized so long as the original energizing circuit for the relay 516 is maintained.

40 Another result of the operation of the relay 514 is that a circuit is closed for the relay 505. The relay 505 operates to establish a locking circuit for itself at armature 529 and to place ground upon conductor 454. By the grounding of conductor 454, a circuit is completed 45 extending from ground by way of armature 682 and its front contact, front contact and armature 630, armature 660 and its back contact, relay 612, armature 684 and its back contact, back contact and armature 680, and armature 683 and its back contact to battery.

The relay 612 is energized over the above 55 circuit and operates to remove ground from the conductor 456 at armature 668, to prepare a circuit for the relay 613 at armature 656, and to complete a circuit at armature 655 that extends from ground upon conductor 453, that has been previously grounded by the deenergization of the relay 512, by way of armature 655 and its front contact, armature 657 and its back contact, conductor 452, relay 502, and back contact and armature 526 to battery. The relay 502 is energized to open the circuit 60 of the line relays 313 and 514 at armature 524.

The relay 514 is deenergized to remove the short-circuit from the relay 515. The relay 515 is operated to remove battery from conductor 458 at armature 554, and to complete a circuit for the relay 510 at armature 555. The relay 510 is operated to establish a locking circuit for itself at armature 542 and to prepare a circuit for the line relay 511 at armature 541. A still further result of the operation of the relay 510 is that the circuit of the relay 504 is completed. The relay 504 is operated to establish a locking circuit for itself at armature 527, and to open the circuit of the relay 502 at armature 526. The relay 502 is deenergized to prepare a circuit for the line relay 511. 70 75 80

At the dispatcher's office, the line relay 313 is deenergized to remove the short-circuit from the relay 312. The relay 312 is operated to remove ground from the conductor 22 at armature 338, and to complete the circuit of the relay 317 at the front contact of this armature. The relay 317 is energized to establish a locking circuit for itself at armature 351 and to prepare a circuit for the line relay 316. 90 The driving circuit is now completed and the line relays 316 and 511 are energized in series.

The line relay 316, upon operating, places ground upon conductor 23 at armature 348, and at armature 349 completes a circuit for the relay 314. The relay 314 is operated to open the circuit of the relays 311 and 312 and to prepare a circuit for the relay 315. The relay 312 is deenergized to open the original energizing circuit of the relay 317 at armature 338. The relay 311 is deenergized to complete a circuit for the relay 315. The relay 315 is short-circuited so long as the original energizing circuit of the relay 314 is completed. 100 105

By the grounding of conductor 23, a circuit is completed that extends by way of this conductor, armature 188 and its front contact, front contact and armature 150, armature 179 and its back contact, counting relay 123, armature 185 and its back contact, back contact and armature 158, and back contact and armature 187 to battery. The relay 123 is energized to complete a circuit for the relay 122 at armature 182, and to complete a circuit at armature 181 that extends from ground on grounded conductor 22 by way of armature 181 and its front contact, armature 176 and its back contact, conductor 21, back contact and armature 326, and relay 307 to battery. The relay 307 is energized to open the driving circuit at armature 331 to place battery upon conductor 29 at armature 330 and to establish a locking circuit for itself at armature 395 over a path that extends 110 115 120 125 from ground at conductor 24 by way of armature 397 and its back contact, back contact and armature 398, armature 396 and its front contact, armature 395 and its front contact, and relay 307 to battery. 130

At the substation the line relay 511 is operated to complete a circuit for the relay 513. The relay 513 is energized to open the circuits of the relays 515 and 516 and to prepare a circuit for the relay 512. The relay 515 is deenergized to prepare a circuit for the relay 514 and to open the original energizing circuit for the relay 510.

The relay 516 is deenergized to complete a circuit for the relay 512. The relay 512 is short-circuited so long as the original energizing circuit for the relay 513 is maintained. Another result of the deenergization of the relay 515 is that battery is placed upon the conductor 458.

When the driving circuit is opened, as before described, the line relay 316 at the dispatcher's office is deenergized to remove ground from conductor 23 and to remove the short-circuit from the relay 315. The relay 315 is operated to prepare a locking circuit for the relay 304 at armature 344, and to open another point in the circuit of the relay 316. Another result of the operation of the relay 315 is that the locking circuit of the relay 317 is opened. The relay 317 is deenergized to prepare a circuit for the line relay 313.

By the removal of ground from the conductor 23, the short-circuit is removed from the relay 122 and this relay is operated. Upon operating, the relay 122 opens one point in the original energizing circuit of the relay 123 at armature 179, prepares a circuit for the counting relay 109 at armature 178, opens the circuit of the relay 127 at armature 177, opens the original energizing circuit of the relay 307 at armature 176, and at armature 180 completes a circuit extending from ground by way of armature 183 and its back contact, armature 147 and its back contact, front contact and armature 180, conductor 20, selecting relay 216, conductor 29, and front contact and armature 330 to battery.

The selecting relay 216 is energized over the above circuit and operates to prepare a circuit for the signaling device 243 at spring 270, to prepare a signaling circuit at spring 271, to prepare a control circuit at spring 272 and to prepare a circuit for placing ground upon the conductor 27 at spring 273.

When the relay 307 is energized as before described the circuit of the slow-releasing relay 305 is opened and this relay is deenergized after an interval of time to close a circuit that extends from ground by way of back contact and armature 328 conductor 28, spring 270 and its working contact, and signaling device 243 to battery. The operation of the signaling device informs the dispatcher of the selecting operation and that the signaling devices 226 and 227 are connected to the signaling circuit.

At the substation, the line relay 511 is deenergized by reason of the fact that its cir-

cuit is opened by the operation of the relay 307. The relay 511 is deenergized to remove the short-circuit from the relay 512. Upon operating, the relay 512 opens one point in the circuit of the relay 511 at armature 547, opens another point in the original energizing circuit of the relay 513 at armature 546, opens the locking circuit of the relays 504 and 505 at armature 545, and at armature 544 removes ground from conductor 453.

The relay 505 is immediately deenergized to remove ground from conductor 454. The removal of ground from conductor 454 causes the energization of the relay 613 by reason of the fact that the short-circuit is removed from this relay. Upon operating, the relay 613 opens one point in the original energizing circuit of the relay 612 at armature 660, prepares a circuit for the counting relay 602 at armature 659, opens the circuit of the relay 690 at armature 658, and at armature 657 opens one point in the circuit which places ground upon the conductor 452.

A still further result of the operation of the relay 613 is that a circuit is completed extending from ground by way of armature 686 and its back contact, armature 634 and its back contact, front contact and armature 661, conductor 472, selecting relay 405, conductor 458, and back contact and armature 554 to battery. The selecting relay 405 is operated to place ground upon conductors 459 and 457 at springs 428 and 427, respectively, to prepare a signaling circuit at spring 426 and to prepare control circuits at springs 424 and 425.

The grounding of conductor 459 completes a circuit for the relay 706. The relay 706 is energized to prepare a circuit for the relay 700 at armature 732. The grounding of conductor 457 causes the energization of the relay 518. The relay 518 is operated to complete a circuit for the relay 517. The relay 517 is energized to open the locking circuit of the relay 510. The relay 510 is operated to open the circuit of the relay 504 at armature 540, and to prepare a circuit for the line relay 514 at armature 541. The relay 504 is deenergized to prepare a circuit for the relay 502.

The operations by which the selecting relay 405 is energized are brought about by the operation of the relay 307 in the same manner that the operations by which the selecting relay 216 is energized. The selecting relays 216 and 405 are thus energized substantially simultaneously.

From the circuits thus far traced, it will be noted that, upon the operation of the first drive circuit through the line relays 313 at the office and 514 at the substation, at the substation the first of the counting relays 600 was energized following the energization of the relay 505. Following the energization of the relay 600, the relay 502 was energized to open

the drive line to complete the second half of the first drive operation and shift the driveline from relay 514 to relay 511. At the dispatcher's office, nothing of importance happened, except that the drive line was shifted so as to connect the relay 316 to the drive circuit.

The second drive operation resulted in the energization of the relay 111 followed by the energization of relay 307 which opened the drive line to perform the second half of the second drive operation. Thus, it will be noted, that the counting relay 600 and the counting relay 111 are operated alternately. However, upon the completion of the second half of the second drive operation, the shunts of the relays 110 and 601 are removed and the relays 111 and 110 are operated in series, simultaneously, with the relays 600 and 601. That is, the counting relay at the office and the counting relay at the substation are first operated alternately, followed by the simultaneous operation of the counting relays at the office and the substation.

It will be remembered that the dispatcher desires to close the circuit interrupter C in order to bring about certain operations at the substation. To accomplish this result, when the dispatcher is informed, by the operation of the signaling device 243, that the selecting action is completed, he will operate the control device 200.

As the key K-1 has been previously operated by the dispatcher, when the selecting relays 216 and 405 are operated, a circuit is completed that extends from ground by way of the springs of key K-1, springs of the control device 200, working contact of spring 218 and said spring, front contact and armature 224, working contact of spring 272 and said spring, conductor 31, front contact and armature 332, conductor 370, armature 520 and its front contact, conductor 463, relay 700, and front contact and armature 732 to battery. The relay 700 is energized over the above circuit and operates to open the circuit of the slow-releasing relay 702 at armature 722, and to prepare an impulsive circuit at the front contact of this armature. Another result of the operation of the relay 700 is that a circuit is completed for the slow-releasing relay 701 at armature 724. When the slow-releasing relay 702 is deenergized after a short interval of time, a circuit is prepared for placing ground upon conductors 460 and 462. The slow-releasing relay 701 is energized to prepare a circuit for the counting relay 711 at armature 725.

Now, when the control device 200 is operated, two interruptions are produced in the circuit that includes the relay 700 at the substation. Upon the first deenergization of the relay 700, the circuit of the slow-releasing relay 701 is opened at armature 724, and at the back contact of this armature, an impulse is sent over a circuit that extends from ground

by way of armature 724 and its back contact, armature 725 and its front contact, armature 738 and its back contact, counting relay 711, back contact and armature 753, back contact and armature 731, and back contact and armature 727 to battery.

The relay 711 is energized over the above-traced circuit and operates to complete a circuit that extends from ground by way of back contact and armature 729, armature 740 and its front contact, relay 710, relay 711, back contact and armature 753, back contact and armature 731, and back contact and armature 727 to battery. The relay 710 is not energized by reason of the fact that it is short-circuited so long as the original energizing circuit of the relay 711 is completed. Another result of the operation of the relay 700 is that a circuit is completed for the slow-releasing relay 702. The relay 702 is energized to open one point in the control circuit.

When the relay 700 is energized, the original circuit of the relay 711 is opened at armature 724 and also the circuit of the slow-releasing relay 702 at armature 722. By the opening of the original circuit for the relay 711, the relay 710 is permitted to operate. Upon operating, the relay 710 places ground upon conductor 468 at armature 739, prepares a circuit for the counting relay 713 at armature 738, and at armature 737 prepares a circuit for the relay 703.

The grounding of conductor 468 brings about the energization of the relay 501. The relay 501 is energized to complete a locking circuit for itself at armature 522, and to open another point in the driving circuit at armature 523. The locking circuit of the relay 501 extends from battery by way of relay 501, front contact and armature 522, conductor 467, and back contact and armature 728 to ground.

Upon the next deenergization of the relay 700, a circuit is completed that extends from ground by way of armature 724 and its back contact, armature 725 and its front contact, armature 738 and its front contact, armature 742 and its back contact, relay 713, back contact and armature 753, back contact and armature 731, and back contact and armature 727 to battery. The relay 713 is energized over this circuit and operates to complete a circuit extending from ground by way of back contact and armature 729, armature 743 and its front contact, relay 712, relay 713, back contact and armature 753, and back contact and armature 731 to battery. This circuit is not effective so long as the original energizing circuit for the relay 713 is maintained.

When the relay 700 is energized, at the termination of this impulse series, the circuit of the relay 713 is opened and the short-circuit is removed from the relay 712, thereby permitting this relay to operate. Upon oper-

ating, the relay 712 prepares a circuit for the counting relay 715 at armature 742, and at armature 741 prepares a circuit for placing ground upon conductor 460. The slow-releasing relay 702 is maintained energized during the interruptions produced in the circuit of the relay 700 by reason of its sluggish action. However, when the relay 700 is energized at the termination of the impulse series, the circuit of the relay 702 is permanently opened and this relay is deenergized after a short interval of time.

A circuit is now completed that extends from ground by way of armature 722 and its front contact, armature 726 and its back contact, front contact and armature 741, armature 744 and its back contact, conductor 460, spring 425 and its working contact, front contact and armature 418, and relay 401 to battery. The relay 401 is operated to complete a circuit for the closing coil 404 of the circuit interrupter C. The closing coil 404 operates to close the circuit breaker.

When the circuit interrupter is closed, the circuit of the closing coil 404 is opened at the auxiliary switch 423, and at the auxiliary switch 422 the circuit of the slow-releasing relay 400 is opened, and a circuit is momentarily completed that extends from ground by way of said auxiliary switch, armature 415 and its front contact, conductor 455, armature 531 and its back contact, conductor 465, armature 733 and its back contact, and relay 708 to battery. The relay 708 is energized to complete a circuit that extends from ground by way of armature 736 and its back contact, armature 735 and its front contact, relay 707 and relay 708 to battery. This circuit is not effective until the original energizing circuit for the relay 708 is opened.

The slow-releasing relay 400 is deenergized after a short interval of time to place battery upon the conductor 450 at armature 419, to open the circuit of the relay 401 at armature 418, to prepare a circuit for the relay 402 at armature 417, and to open the original energizing circuit of the relay 708 at armature 415. This latter operation removes the short-circuit from the relay 707 and this relay is operated to open another point in the original circuit of the relay 708 at armature 733, and at armature 734 to place ground upon conductor 455.

When battery is placed upon conductor 450, a circuit is completed that extends by way of said conductor, front contact and armature 521, trunk conductor 371, armature 333 and its front contact, conductor 30, spring 271 and its working contact, armature 232 and its back contact, and relay 205 to ground. The relay 205 is energized to attract the armature 231, whereby the armatures 228, 229 and 230 of the relay 204 are permitted to assume their normal position.

By the operation of the armature 228, the

circuit of the signaling device 227 is opened and a circuit is completed for the signaling device 226. The operation of the armature 229 completes a circuit for the slow-releasing relay 206, while the operation of the armature 230 opens one point in the circuit of the relay 202.

The relay 206 is operated to open the circuit of the relay 205, to prepare a circuit for the relay 204 at armature 232, and to complete a circuit at armature 233 which extends from ground by way of spring 221 and its working contact, armature 233 and its front contact and relay 203 to battery. The relay 205 is deenergized to permit its armature 231 to restore to normal. The relay 203 is energized to attract the armature 225, thereby permitting the armatures 223 and 224 of the relay 202 to assume their normal positions.

By the operation of the armature 224, a circuit is prepared for connecting the control device 201 to the control circuit and the circuit of the relay 700 at the substation is opened. By the operation of the armature 223, ground is placed upon the conductor 27 over a circuit that extends from ground by way of spring 221 and its working contact of key K-3, back contact and armature 223, springs of key K-13, working contact of spring 273 and said spring to conductor 27.

The grounding of conductor 27 closes a circuit for the relay 309 and the latter operates to complete a circuit for the relay 304 at armature 334, and to open the locking circuit of the relay 307 at armature 397. The relay 304 is operated to open one point in the original energizing circuit of the relay 307 at armature 326 and to establish a locking circuit for itself at armature 327. The relay 307 is deenergized to remove battery from conductor 29, to complete a circuit for the slow-releasing relay 305 at armature 330, and to complete one point in the driving circuit at armature 331.

By the removal of battery from conductor 29, the circuit of the selecting relay 216 is opened and this relay is deenergized to open the control and signaling circuits at springs 271 and 272, to open the circuit of the signaling device 243 at spring 270, and to open the circuit of the relay 309 at spring 273. The relay 309 is deenergized to open the original energizing circuit of the relay 304 at armature 334, and to prepare a locking circuit for the relay 307 at armature 397.

When the circuit of the relay 700 is opened, as previously described, this relay is deenergized. The retraction of the armature 722 causes the removal of ground from conductor 460 and the completion of a circuit for the relay 702. The retraction of the armature 724 opens the circuit of the slow-releasing relay 701 and completes a circuit for the counting relay 715. This relay is operated to prepare a circuit for the relay 714. When the

slow-releasing relay 701 is opened, the relay 714 is operated to prepare a circuit for the relay 717. The operation of the relays 714 and 715 is without particular function at the 5 present time.

By the deenergization of the relay 701, a circuit is completed that extends from ground by way of armature 724 and its back contact, armature 725 and its back contact, relay 10 703, and armature 737 and its front contact to battery. The relay 703, upon operating, opens the circuit of the counting relays 710 to 715, inclusive, at armature 727, and at armature 728 removes ground from conductor 467. 15 The relays 710 to 715, inclusive, are deenergized to restore certain circuits to normal.

The deenergization of the relay 710 removes ground from conductor 468, whereby the original energizing circuit of the relay 501 is 20 opened. The deenergization of the relay 710 also opens the circuit of the relay 703. The removal of ground from conductor 467 by the energization of the relay 703 opens the locking circuit of the relay 501. The relay 501 is 25 deenergized to complete the driving circuit. The relay 703 is deenergized to prepare certain circuits. The line relays 313 and 514 are now energized in series.

As a result of the third drive operation, 30 the relay 612 at the substation is energized, followed upon the operation of the next drive impulse by the energization of the relay 123. During the second half of this drive impulse relays 613 and 122 are operated simultaneously. The energization of the relay 122 completes an energizing circuit for the first selecting relay 216 while the energization of the relay 613 completes an energizing circuit for the first selecting relay 405. Upon the 35 operation of the last half of the fourth drive impulses just traced, the relay 315 is energized to open the locking circuit for the relay 317. The relay 310 is energized to open the locking circuit for the relay 307. At the substation, the locking circuit for the relay 510 is 40 opened at armature 558 and the relay 510 is deenergized. The relay 519 is energized upon the operation of the selecting relay 405, to, in turn, complete an energizing circuit for relay 517 and a driving circuit is completed similar to the first drive circuit traced, including the relay 313 at the office and 514 at the substation.

The energization of the relay 514 at the substation energizes the relay 505 which, in turn, completes an energizing circuit for the relay 502 which thereupon opens the drive circuit. In the meanwhile the energization of the relay 313 at the office performs no particular function, except to prepare to transfer the drive circuit from the relay 313 to relay 316. During the second half of the drive operation, this transfer is completed at the office, and a similar transfer is completed 60 from relay 514 to 511 at the substation, fol-

lowing which the relay 502 is deenergized and the drive circuit is again closed, this time including relay 316 at the office and relay 511 at the substation.

The energization of the relay 316 completes 70 an energizing circuit for the relay 109, which, in turn, energizes the relay 307 and the drive circuit is opened. During this time, no particular function is performed at the substation, except to prepare to transfer the drive 75 circuit from relay 511 to 514. Upon the opening of the drive circuit at this time, relay 108 at the office and relay 603 at the substation are energized, simultaneously. These, in turn, will close circuits for the selecting relays 80 215 at the office and 406 at the substation, respectively.

The driving circuit functions, in the manner described, to control the operation of the relays 109, 108, 121, 120, 107, 106, 119, 118, 105, 104, 117, 116, 103, 102, 115, 114, 101, 100, 113 and 112 in the sequence mentioned. By the operation of the counting relays up to and including the relay 100, the selecting relays are 90 operated in the following sequence, 215, 214, 213, 212, 211, 210, 209, 208 and 207.

At the substation, the functioning of the driving circuit brings about the operation of the counting relays 602, 603, 614, 615, 604, 605, 616, 617, 606, 607, 618, 619, 608, 609, 620, 621, 610, 611, 622 and 623. The operation of the counting relays up to and including the relay 611 causes the operation of the selecting relays in the following sequence, 406, 407, 408, 409, 410, 411, 412, 413 and 414. 100

During the operation of the selecting relays, the control and signaling circuits function in a manner similar to that already described. That is, if the dispatcher desires to control another circuit interrupter, the key corresponding to such interrupter at the dispatcher's office, similar to the key K-3, will be operated in the proper direction. By this operation, the driving circuit is prevented from operating until the dispatcher has controlled such interrupter and has received an answer-back signal indicative of its operation. 110

In the event that there are no other controlling operations performed by the dispatcher, the selecting operation will take place under the control of the driving circuit without hesitation. This is apparent from the circuits above traced, from which it is seen that the drive circuit functions upon each operation to operate the relay chains and to transfer its own circuit while the relay chain, in turn, holds the drive circuit open. The deenergization of the relay 307, which is necessary in order to permit the drive operation to continue, depends upon the energization of either relay 309 or 310. Since these relays obtain their ground over the contacts equivalent to keys K-3, K-4, and the operating keys K-3, it is evident that the operation will 115 120 125 130

continue without hesitation unless one of these keys are opened. Should one of these keys be open, one of these relays 309 or 310 will fail to get energy, thereby preventing the

5 opening of the locking circuit for relay 307 which, in turn, prevents the drive circuit from operating. However, the operation of the selecting relays in each case closes signaling circuits for relays similar to relays 204 and 10 205 at the dispatcher's office so that the condition of the signaling devices, similar to devices 226 and 227, is checked in order to insure that such signaling devices indicate the proper condition of their corresponding 15 circuit interrupters. If, for any reason, the condition of the signaling devices and the circuit interrupter does not correspond, the signaling circuit will be completed to energize a relay, such as 204 or 205, to bring about the 20 proper change in signals.

The completion of the signaling circuit and the change in the signaling devices does not take any appreciable time, so it is not necessary to interrupt the action of the driving circuit until such signals are received. This is especially true in view of the fact that the corresponding selecting relays at the dispatcher's office and substation are energized substantially simultaneously so that the signaling circuit is closed at both the dispatcher's office and substation.

When the relay 113 is energized by the operation of the line relay 316, the circuit of the selecting relay 207 is opened at armature 161, 35 a circuit is completed for the relay 112 at the front contact of this armature, and at armature 160 a circuit is completed that extends from ground upon grounded conductor 24 by way of armature 338 and its back contact, 40 conductor 22, armature 160 and its front contact, armature 156 and its back contact, conductor 21, back contact and armature 326, and relay 307 to battery.

The relay 307 is energized to open the circuit of the slow-releasing relay 305 at armature 330, to place battery upon conductor 29 at the front contact of this armature, and to open the driving circuit at armature 331. By the opening of the driving circuit, the relay 50 316 is deenergized and the short-circuit is removed from the relay 112.

The relay 112, upon operating, removes the short-circuit from the relay 125 at armature 158, opens the circuit of the relay 127 at armature 157, and at armature 156 opens the original energizing circuit of the relay 307. The relay 125 operates to complete a circuit for the slow-releasing relay 124 at armature 186. The slow-acting relay 124 is energized to open 60 the circuits of all the relays 100 to 123, inclusive, and relay 125 at armature 183, to remove ground from conductor 24 at armature 184, and to place ground upon the conductor 25 at the front contact of this armature. 65 The counting relays 100 to 123, inclusive, are

deenergized to restore their circuits to normal condition. The relay 125 is also deenergized to open the circuit of the slow-releasing relay 124.

The removal of ground from conductor 24 70 opens the circuits of the relays 314 and 315, and also the circuit of the relays 317. These relays are deenergized to restore certain circuits to normal. By the connection of ground to conductor 25, the relay 300 is energized. The relay 300 operates to establish a locking circuit for itself at armature 318, to open the circuits of the relays 302 and 303 at armature 319, and to open the circuit of the relay 306 at armature 320. The relay 306 80 is deenergized to open one point in the driving circuit.

The relay 302 is deenergized to open one point in the circuit of the relay 303. The relay 303 is deenergized to prepare a circuit 85 for the holding relay 301 at armature 325. By the removal of ground from conductor 24, the locking circuit of the relay 307 is opened and this relay is deenergized to complete a circuit for the slow-releasing relay 90 305 and to remove battery from conductor 29. The deenergization of the counting relay 110, previously described, brings about the deenergization of the relay 308. The relay 308 retracts its armatures to open certain 95 points in the signaling and control circuits and to prepare a circuit for the holding relay 301.

At the substation, the relay 623 is energized indirectly by the operation of the line relay 511. That is, the line relay 511 is energized to complete a circuit for the relay 513. The relay 513 is operated to prepare a circuit for the relay 512. When the driving circuit is opened by the energization of the relay 307, as previously described, the relay 511 is deenergized, whereby the short-circuit is removed from the relay 512. The relay 512 is operated to open the locking circuit of the relay 505. The relay 505 is deenergized to 100 remove the short-circuit from the relay 623. 105

The relay 623, upon operating, removes the short-circuit from the relay 625 at armature 680, opens the circuit of the relay 690 at armature 679, and at armature 678 opens one point in the circuit of the relay 502. The relay 625, upon operating, completes a circuit for the slow-releasing relay 626 at armature 685. The slow-releasing relay 626 operates to open the circuits of the relays 600 to 623, inclusive, and the relay 625 at armature 686, to remove ground from conductor 469 at armature 687, and to connect ground to conductor 466 at the front contact of this armature. The counting relays 600 to 623, inclusive, are deenergized to restore certain circuits to normal. The relay 625 is deenergized to open the circuit of the slow-releasing relay 626. 115 120 125

By the removal of ground from conductor 130

469, the circuits of the relays 512 and 513 are opened. These relays are deenergized to restore certain circuits to normal. By the energization of the relay 626, the circuit of the relay 500 is opened, and this relay is deenergized to open certain points in the signaling and control circuits and to prepare a holding circuit for the relay 506.

- The connection of ground to conductor 10 466 completes a circuit for the relay 509. The relay 509 is energized to establish a locking circuit for itself at armature 537, to open the circuit of the relays 507 and 508 at armature 538, and to open the circuit of the relay 15 503 at armature 539. The relay 508 is deenergized to open one point in the circuit of the relay 507. The relay 507 is deenergized to prepare a circuit for the holding relay 506. The relay 503 is deenergized to 20 open another point in the driving circuit.

The holding circuit is now completed over a path that extends from ground by way of relay 301, back contact and armature 325, back contact and armature 332, conductor 25 370, armature 520 and its back contact, relay 506, and armature 534 and its back contact to battery. The relays 301 and 506 are energized over this circuit.

Upon operating, the relay 301 opens the 30 locking circuit of the relay 300 at armature 321, and at armature 322 opens another point in the circuit of the relay 306. The relay 300 is deenergized to prepare a circuit for the relay 306 at armature 320, and to prepare a 35 circuit for the relay 303 at armature 319.

At the substation, the relay 506 is operated to open the locking circuit of the relay 509 at armature 530, to prepare a starting circuit at armature 531, and to open another 40 point in the circuit of the relay 503 at armature 532. The relay 509 is deenergized to prepare a circuit for the relay 507 at armature 538, and to prepare a circuit for the relay 503 at armature 539.

45 It will be remembered that the conductor 455 has been previously grounded by the operation of the relay 707 immediately after the operation of the circuit interrupter C. Now, when the relay 506 is energized, a circuit is completed for the relay 508. The relay 508 is operated to complete a circuit for the relay 507. The relay 507 is not energized until the original circuit of the relay 508 is opened. By the operation of the relay 508, a 55 circuit is completed extending from ground by way of armature 530 and its front contact, front contact and armature 535, conductor 464 and relay 709 to battery.

The relay 709 is operated to open the 60 circuits of the relays 707 and 708 at armature 736. The relay 708 is deenergized to open one point in the circuit of the relay 707. The relay 707 is deenergized to open the previously mentioned circuit for the relay 508. 65 By this operation, the circuit of the relay 507

becomes effective. The relay 507, upon operating, opens the holding circuit which includes the holding relays 506 and 301.

The selecting operation now occurs in substantially the same manner as before described. In this case, however, only signaling operations will occur by reason of the fact that the dispatcher has not operated any control keys. The reason that the selecting operation is again initiated is to insure that 75 the supervisory indications for the dispatcher indicate the true condition of the corresponding apparatus units at the substation. The release of the apparatus is brought about in substantially the same manner as 80 before described.

When the selecting apparatus is used to operate apparatus units that are also controlled by the usual form of automatic devices that are responsive to circuit conditions, it becomes necessary to initiate the automatic operation of the selecting devices immediately upon the automatic operation of an apparatus unit at the substation. To describe this 85 operation, it will be assumed that the circuit interrupter C is in the position shown and that it is operated automatically by the 90 operation of the circuit responsive devices (not shown).

When the circuit breaker is operated, the 95 circuit of the slow-releasing relay 400 is opened at auxiliary switch 422 and a circuit is momentarily completed that extends from ground by way of auxiliary switch 422, armature 415 and its front contact, conductor 100 455, armature 531 and its front contact, armature 533 and its back contact, and relay 508 to battery. The relay 508 is energized to complete a circuit for the relay 507.

When the slow-releasing relay 400 is 105 finally deenergized, the circuit for the relay 508 is opened. The circuit that includes the relays 507 and 508 then becomes effective. The relay 507 is operated to open the holding circuit that includes the relays 301 and 506. By this operation, the selecting apparatus is caused to function in the manner 110 described.

Had the circuit interrupter C been closed and the dispatcher desired to open it, the operation would proceed in substantially the same manner as before, with the exception that the key K-3 at the dispatcher's office would be in the position shown and the control device 201 would be connected. The dispatcher would then operate the control device 201, whereby four interruptions would be produced in the circuit of the relay 700. The operation of the relay 700 would bring about the energization of the relays 710 to 120 717, inclusive, with the result that, after the impulse series, the deenergization of the relay 702 would close the circuit for the relay 402 over a circuit from ground by way of armature 722 and its front contact, arma- 125 130

ture 726 and its back contact, front contact and armature 754, armature 755 and its back contact, conductor 461, back contact and armature 417, winding of relay 402, and battery to ground. The relay 402 would bring about the tripping of the circuit interrupter C. The supervisory signals would be returned to the dispatcher's office in a manner similar to that described. When a circuit breaker moves from its open to its closed position, the relay 400 is deenergized. It will be noted that the armature 419 on its front contact is grounded, whereas on its back contact connects battery to the conductor 450. If the circuit breaker closed, this relay deenergizes and instead of grounding the supervisory line 371 over conductor 450 and armature 521, battery is placed upon this conductor and the equivalent relay at the office is thus energized. Similarly, if the circuit should operate from its closed to its open position, the relay 400 previously deenergized will become energized to remove battery and place ground on the line.

The foregoing describes all normal operation of the system. Certain circuit arrangements have been provided to take care of circumstances that may arise to cause false operation and these will now be described.

It will be seen that, during the control operation, the driving circuit is opened at both the dispatcher's office and substation by the operation of the relay 307 and the relay 501. Consequently, no inductive surges in the driving circuit will cause any false operation of the selecting apparatus. Also, by reason of the fact that it is necessary to interrupt the circuit of the relay 700 a predetermined number of times in order to cause an action, any induced disturbances which cause a greater or lesser number of operations will bring about no operation of the circuit interrupter C.

By reason of the fact that it is necessary to produce a predetermined number of interruptions in the circuit of the relay 700 in order to cause the operation of an apparatus unit at the substation, no induced currents will be effective to cause such operations. At least, the possibility of such induced currents causing the characteristic number of interruptions in the circuit of the relay 700 is very remote; so remote, in fact, that it may be considered negligible.

The starting circuit by which the selecting action of the relay apparatus is initiated is so arranged that such action will occur, even though the operation of the apparatus units or circuit interrupters occurs manually or by reason of some mechanical defect in the circuit interrupter, inasmuch as the auxiliary switches, such as 422, on each circuit interrupter are operated whenever the interrupter is actuated, by reason of manual operation or mechanical failure.

The slow-releasing relay 400 is either energized or deenergized. That is, if the circuit breaker is opened and closed, the circuit of the slow-releasing relay 400 will be opened. However, before the deenergization of this relay, ground will be momentarily applied to the starting conductor 455. In the event that the circuit breaker is closed and tripped, the circuit of the slow-releasing relay is closed. This relay is so constructed that it requires an appreciable time to operate its armatures and, consequently, ground is momentarily connected to the starting conductor 455.

With the circuit breaker normally closed, the relay 400 is deenergized. Now if the circuit breaker opens, a circuit is completed from ground over the lower contacts of the pallet switch, armature 416 and its back contact, conductor 455, armature 531, and its front contact, armature 533 and its back contact, winding of relay 508 and battery to ground. Simultaneously, with this, an energizing circuit is completed for the relay 400, which, being slow to operate, energizes after an interval of time and opens this circuit just traced, at armature 416. As a result, the original energizing circuit for the relay 508 is opened and the series circuit for the relays 507 and 508 over armature 536 becomes effective. The energization of the relay 507 opens the normal energizing circuit previously traced at armature 534. The driving circuit now functions in a manner already described.

Attention is directed to the fact that each time the relay 307 is energized to open the driving circuit, the selecting relay must operate in order to bring about the operation of one of the relays 309 or 310 before the driving circuit is again closed. Consequently, the selecting action is interrupted until it is assured that the proper counting relay of the group 100 to 123, inclusive, and the proper selecting relay of the group 207 to 216, inclusive, are operated.

The dispatcher is also provided with means for bringing about the release of the selecting apparatus at the dispatcher's office and substation whenever he desires.

In order to bring about the release of the apparatus at the substation, the dispatcher will operate the release key K-16 and the release control device 290. By the operation of the key K-16, ground is removed from the conductor 291 that extends to all the apparatus control keys, such as K-3. This brings about the interruption of the driving circuit at any selecting position in which it is at the time that one of the selecting relays at the dispatcher's office and the corresponding selecting relay at the substation energize.

The operation of the key K-16 also completes a circuit for the relay 700 at the substation. By the operation of the release de-

vice 290, six interruptions are produced in the circuit of the relay 700. By the deenergizations and energizations of the relay 700, the counting relays 710 to 721, inclusive, are 5 operated. Immediately upon the operation of the counting relay 720, a circuit is completed that extends from ground by way of armature 755 and its front contact, conductor 470, and relay 624 to battery. The relay 624 10 is energized to remove the short-circuit from the relay 625. The relay 625 is operated to bring about the release of the relay selecting apparatus at the substation in the same manner as before described.

15 The operation of the relay 720 also removes the short-circuit from the relay 705 at armature 753. The relay 705, upon operating, completes a circuit for the slow-releasing relay 704 and opens the circuits of all the counting 20 relays 710 to 721, inclusive. The counting relays 710 to 721, inclusive, are deenergized to restore certain circuits to normal.

The slow-releasing relay 704, upon being operated, opens another point in the circuit 25 of the counting relays. The deenergization of the counting relays brings about the deenergization of the relay 705 which operates to open the circuit of the relay 704. After a short interval of time, the relay 704 is deenergized. In this manner, the apparatus at 30 the substation is restored to normal.

In order to release the apparatus at the office, the dispatcher will operate the key K of Fig. 1. This operation brings about the 35 removal of the short-circuit from the relay 125. A condenser shunts the contacts of armatures 183, 184, 185 and 187 in order to protect them from arcing. The operations that are brought about by the energization of the 40 relay 125 whereby the apparatus at the office is released have been previously described.

The dispatcher may desire to select a predetermined apparatus unit and remain in connection therewith in order to operate it 45 a plurality of times and observe its functioning. In order to accomplish this result, the dispatcher will operate one of the keys, such as key K-13, associated with this particular apparatus unit. As a result of this operation, the circuit of one of the relays, such as relay 50 309 or 310, is permanently opened until the restoration of the key. Thus, when the key K-13 is operated, the circuit of the relay 309 is opened so that no operation of the relays 202 to 206, inclusive, is without function 55 to bring about its energization. Consequently, the dispatcher may operate the circuit interrupter C as often as he desires. Each operation of the circuit interrupter C causes the 60 proper answer-back signal to be returned to the dispatcher's office in order to apprise the dispatcher of the position of this unit. After the dispatcher is through observing the function of this unit, he will restore the key K-13 65 to normal, whereby the relay 309 is energized

and the driving circuit is again effective to operate the relay selecting apparatus.

In the system described, only sufficient apparatus has been shown to supervise and control the action of ten apparatus units. However, the capacity of the system may be increased by providing additional groups of selecting relays similar to the relay group 207 to 216, inclusive, with switching relays to connect these selecting relays under the control of the counting relays 100 to 123, inclusive, at the proper time. Similar apparatus may be provided at the substation. This manner of increasing the capacity of the system has been previously described in copending application Serial No. 699,670, filed March 17, 1924, T. U. White, and assigned to the Westinghouse Electric & Manufacturing Company.

Our invention is not limited to the particular arrangement of the apparatus described, but may be variously modified without departing from the spirit and scope thereof, as set forth in the appended claims.

We claim as our invention:

1. In a signaling system, the combination with a dispatcher's office and a station, of a group of relays at said office and a group of relays at said station, a driving circuit comprising conductors less in number than the number of relays extending between said office and said station for controlling the operation of the relays in each group, means controlled by said driving circuit for operating a relay in the group at said station and for then operating a relay in the group at said office, and additional means controlled by the operation of the relay in the group at said station for causing said driving circuit to simultaneously operate a relay in each group.

2. In a signaling system, the combination with a dispatcher's office and a station, of a group of relays at said office and a group of relays at said station, a driving circuit comprising conductors less in number than the number of relays extending between said office and said station for controlling the operation of the relays in each group, a pair of line relays at said station and said office, switching means for connecting said driving circuit at each point to said line relays alternately, means controlled when one of said line relays at said office and one of said line relays at said station are operated for operating a relay in the group at said station, and means controlled when the other relay at each point is operated for operating a relay in the group at said office.

3. In a signaling system, the combination with a dispatcher's office and a station, of a group of relays at said office and a group of relays at said station, a driving circuit comprising conductors less in number than the number of relays extending between said of-

5 fice and said station for controlling the operation of the relays in each group, first and second line relays at said station and said office, respectively, switching means for connecting said driving circuit at each point to said line relays alternately, means controlled when one of said line relays at said office and one of said line relays at said station are operated for operating a relay in the group at 10 said station, and means controlled by the operation of the second relay in each group for again operating said switching means to connect said driving circuit to said first line relays.

15 4. In a signaling system, the combination with a dispatcher's office, a station, a group of counting relays at said office and said station and a group of selecting relays associated with each group of counting relays, of a driving circuit comprising conductors less in number than the number of said counting relays, means controlled by said driving circuit for first causing an operation of a relay in the counting relay group at said station and for 20 then causing an operation of a relay in the counting relay group at said office, means for subsequently operating said driving circuit to cause an operation of a relay in each counting relay group simultaneously, and means 25 controlled by the simultaneous energization of a counting relay in each group for operating a selecting relay in each group.

30 5. In a signaling system, comprising a dispatcher's office, a station, a group of relays at said office, a group of relays at said station, and circuit interrupters at said station, the combination with a driving circuit for operating the relays in said groups in synchronism to select said circuit interrupters in a predetermined sequence during a single cycle of 35 operations, of means for interrupting the action of said driving circuit when any predetermined circuit interrupter is selected, and means at said station responsive only to 40 a predetermined code of impulses and operative at said selecting position at which the drive circuit action was interrupted for closing said circuit interrupter.

45 6. In a signaling system, comprising a dispatcher's office, a station, a signaling line connecting said office and station, a group of relays at said office, a group of relays at said station, said groups of relays each having a normal position and a plurality of apparatus 50 units at said station, the combination with a driving circuit for operating the relays in said groups in a predetermined sequence to associate said apparatus units with said signaling line in synchronism, of an impulse sending device at said office for sending impulses over said line, and means controlled by said device for releasing the relay selecting apparatus from any position to its normal 55 position.

60 7. In a signaling system, comprising a dis-

patcher's office, a station, a signaling line connecting said office and station, a group of relays at said office, a group of relays at said station, each group having a normal position, and a plurality of apparatus units at said station 70 under control of said relays, the combination with a driving circuit for operating the relays in said groups in a predetermined sequence to associate said apparatus units with said line in a predetermined sequence, of an impulse sending device at said office transmitting impulses over said line, and means controlled by said device for releasing the relay selecting apparatus at said station from any selecting position to normal responsive to a 75 predetermined impulse code.

8. In a signaling system, comprising a dispatcher's office, a station, a group of relays at said office, a group of relays at said station, each group having a normal position, and a 80 plurality of apparatus units at said station, the combination with a driving circuit for operating the relays in said groups in synchronism to select said apparatus units in a predetermined sequence, of a device at said 85 station, and means controlled by the operation of said device for releasing the relay selecting apparatus at said station from any selecting position to normal.

9. In a signaling system, comprising a dispatcher's office, a station, a line connecting said office and station, a group of relays at said office, a group of relays at said station, and a plurality of apparatus units at said station individual to and electrically connected 95 to contacts of said relays, the combination with a driving circuit for operating the relays in said groups in a predetermined sequence to sequentially associate said apparatus units with said line in a predetermined sequence, 100 of means for interrupting the action of said driving circuit when any predetermined apparatus unit is associated with said line, and means at said station responsive only to a predetermined code of impulses for operating 105 said unit.

10. In a signaling system, comprising a dispatcher's office, a station, a line connecting said office and station, a group of relays at said office, a group of relays at said station, and a plurality of apparatus units at said station, the combination with a driving circuit for operating the relays in said groups in a predetermined sequence to selectively associate said apparatus units with said line in a 115 predetermined sequence, of means for interrupting the action of said driving circuit when any predetermined apparatus is selected, and an automatic switch at said station responsive only to a predetermined code of 120 impulses transmitted over said line for operating said unit.

11. In a signaling system, comprising a dispatcher's office, a station, a group of relays at said office, a group of relays at said station, 130

- and a plurality of apparatus units at said station, the combination with a driving circuit for operating the relays in said groups in a predetermined sequence to select said apparatus units in a predetermined sequence, of 5 means for interrupting the action of said driving circuit when any predetermined apparatus unit is selected, an automatic switch at said station responsive only to a predetermined code of impulses for operating said 10 unit, and means controlled by the operation of said unit for again operating said driving circuit.
12. In a signaling system, comprising a dispatcher's office, a station, a group of relays at said office, a group of relays at said station, and a plurality of apparatus units at said station, the combination with a driving circuit for operating the relays in said groups 15 in a predetermined sequence to select said apparatus units in a predetermined sequence, of means for interrupting the action of said driving circuit when any predetermined apparatus unit is selected, an automatic switch 20 at said station responsive only to a predetermined code of impulses for operating said unit, means for releasing said switch, and means operative to prevent closure of said driving circuit until said switch is released. 25
13. In a signaling system, comprising a dispatcher's office, a station, a group of relays at said office, a group of relays at said station, and a plurality of apparatus units at said station, a driving circuit for operating the relays in said groups in a predetermined sequence to select said apparatus units in a predetermined sequence, of means for interrupting the action of said driving circuit when any predetermined apparatus unit is selected, 30 an automatic switch at said station responsive only to a predetermined code of impulses for operating said unit, and means controlled by the operation of said switch for opening another point in said driving circuit. 35
14. In a signaling system, a first station, a second station, a signaling line connecting said stations, apparatus units at said second station, selecting apparatus at said first and said second station for consecutively associating each of said apparatus units with 40 said signaling line, means controlled from said first station for bringing said selecting apparatus to a stop at any desired position, means for transmitting a code combination 45 of impulses to said second station and means responsive to said impulses for operating said apparatus unit. 50
15. In a signaling system, a first station, a second station, a signaling line connecting said stations, apparatus units at said second station, synchronously operated distributors for consecutively conditioning each of said apparatus units for operation from said first station, each of said distributors being provided with a position individual to each of 55
- said apparatus units, means controlled from said first station for bringing said distributors to a stop at any one of said positions, and means operative after said distributors have stopped and in response to received 70 code impulses for operating said selected unit individual to said position at which said distributors have stopped. 75
16. In a signaling system, a first station, a second station, a signaling line connecting said stations, synchronously operated distributors at said first and said second stations, apparatus units at said second station, said distributors being provided with a position individual to each of said apparatus 80 units, means controlled by said distributors for controlling the synchronism of said distributors, means controlled from said first station for bringing said distributors to a stop at a selected position, means for transmitting a code of impulses over said first signaling line and means responsive to said code for operating said selected unit. 85
17. In a supervisory control system, a first station, a second station, a signaling line connecting said stations, apparatus units at said second station, means for sequentially associating each of said apparatus units with said signaling line, means whereby said means is operative to maintain a selected unit 90 in association with said signaling line indefinitely under control from said first station and means responsive to a code combination of impulses received over said signaling line for operating said selected unit. 95
18. In a signaling system comprising a dispatcher's office, a station, a line connecting said office and said station, a plurality of apparatus units in said station and selecting apparatus for associating any one of said units with said line, the combination with variable impulse-sending means at said office, of means responsive to the operation of the impulse-sending means over said line for bringing about the operation of the selected unit as often as desired following a selection or releasing the unit from selection without operation in response to predetermined numbers of impulses. 105
19. In a signaling system comprising a dispatcher's office, a station, a line connecting said office and said station, a plurality of circuit interrupters in said station and selecting apparatus for associating any one of said interrupters with said line, the combination with a code-sending means at said office and means responsive to various operations of said code-sending means over said line for bringing about the closure of the selected interrupter, following a selection, as often as desired or the release of the selected interrupter. 115
20. In a signaling system comprising a dispatcher's office, a station, a line connecting said office and said station, a plurality 120
- 125
- 130

of apparatus units in said office and in said station, and relay-selecting apparatus in said office and in said station, the combination with a driving circuit for operating said relay-selecting apparatus through a complete cycle to associate sequentially predetermined apparatus units with said line during said cycle of said relay-selecting apparatus, of a switching device at said station, means for 10 operating said apparatus, said means being

controlled by the operation of said switching device and means, including said line, for operating said switching device to bring about the release of the selecting apparatus at said station. 15

In testimony whereof, we have hereunto subscribed our names this 11th day of November, 1924.

THOMAS U. WHITE.
JOHN E. GARDNER.
